C. NELSON.
LAMP STAND.
APPLICATION FILED FEB. 19, 1914.

1096,185.

Patented May 12, 1914.

UNITED STATES PATENT OFFICE.

CHARLES NELSON, OF NEW YORK, N. Y., ASSIGNOR TO S. STERNAU & COMPANY, A COPARTNERSHIP COMPOSED OF SIGMUND STERNAU AND LIONEL STRASSBURGER, OF BROOKLYN, NEW YORK.

LAMP-STAND.

1,096,185.

Specification of Letters Patent.

Patented May 12, 1914.

Application filed February 19, 1914. Serial No. 819,675.

To all whom it may concern:

Be it known that I, CHARLES NELSON, a citizen of the United States, and a resident of the borough of Brooklyn, city and State of New York, have invented a certain new and useful Lamp-Stand, of which the following is a specification.

This invention relates to a stand for a lamp particularly suited for culinary purposes, the lamp having a body, and a cover which must be removed when the lamp is in use.

The objects of the invention are to produce a simple and inexpensive stand, which may be folded to occupy a minimum amount of space, and which may also be utilized for removing the cover from the lamp. These and further objects will more fully appear from the following specification and accompanying drawings, considered together or separately.

In the drawings, Figure 1 is a plan view of a stand embodying the invention. Fig. 2 is a side view thereof showing one form of lamp in place, and showing, in dotted lines, the stand in folded position. Fig. 3 is a detail bottom plan showing the base and the connection of the legs thereto, the parts being in expanded or open position. Fig. 4 is a similar view, but with the parts in folded position; and Fig. 5 is a side view showing the application of the stand to the lamp in removing the cover of the latter.

In all of the views, like parts are designated by the same reference characters.

The improved stand comprises a base 1, and legs 2 and 3, 3. The base is preferably made of a plate of flat metal; the legs are preferably made of stiff wires. I prefer to use three legs, as shown. The leg 2 is rigidly secured to the base by any means, such as by the rivets illustrated. The legs 3, 3 are pivotally secured to the base by any suitable means, such as by the rivets 4, 4. These legs are so positioned in relation to the leg 2 that they may be folded so as to lie substantially parallel to said leg, as shown in Fig. 4. The base 1 is provided with down-turned lugs 5—5, against which the inner ends of the legs 3—3 will abut when they are moved to the open positions shown in Figs. 1 and 3.

In connection with the base is a lid opener 6. This lid opener is oppositely positioned in said base to the fixed leg 2. It is preferably made by so shaping the material of the base that it forms a tongue, as shown. By turning the legs 3, 3 upon their pivots so that they come alongside of the leg 2, there will be three legs for the operator to grasp in applying the lid opener to the stove. He will be able, therefore, to get an adequate grip even if the legs be of wire of small diameter. As shown in Fig. 5, the lamp 7 has a lid or cover 8. This lid frictionally engages with the opening in the lamp, and has a projecting flange, as shown. The lid opener 6 may be inserted under this flange and the lid lifted. When this is done the legs 3, 3 may be turned upon their pivots, opening the stand, and forming a rest or seat for the lamp 7. When in place, the lamp will rest upon the base 1 and will be encompassed by the three legs, the curved middle portions of the legs engaging with the body of the lamp. The upper parts of the legs, as shown, are bent downwardly and then extend horizontally toward one another so as to form a support for the culinary utensil or other object which is to be held above the flame. The bends at the outer extremities of the legs will serve as a seat to prevent accidental removal of the utensil. The lower legs also curve up, as shown, so as to lift the base above the supporting surface of the stand, thereby protecting the surface from injury caused by the heat of the lamp.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:—

1. A lamp stand which comprises a base, a leg fixedly secured to said base, and a lid opener oppositely positioned on said base to said leg.

2. A lamp stand which comprises a flat

metal base, a leg fixedly secured to said base, there being a portion of said base projecting in line with the leg to form a lid opener.

base projecting in line with the fixed leg, to form a lid opener. ¹⁰

This specification signed and witnessed this tenth day of February, 1914.

CHARLES NELSON.

3. A lamp stand which comprises a flat metal base, a leg fixedly secured to said base, a leg on each side of the first leg pivoted to the base and adapted to fold alongside of said fixed leg, there being a portion of said
